UNITED STATES PATENT OFFICE.

HENRY J. KAHRS, OF NEW YORK, AND CHRISTIAN BODRI AND PETER E. SCHNEIDER,
OF RICHMOND HILL, NEW YORK.

CLOTHESPIN MACHINE.

Application filed February 12, 1925. Serial No. 8,684.

To all whom it may concern:

Be it known that we, HENRY J. KAHRS, citizen of the United States, and resident of the borough and county of Bronx, city and State of New York, and CHRISTIAN BODRI and PETER E. SCHNEIDER, citizens of the United States, and residents of Richmond Hill, in the borough and county of Queens, city and State of New York, have invented certain new and useful Improvements in Clothespin Machines, of which the following is a specification.

Our improvement relates more particularly to an improved clothespin machine, more particularly adapted for the commercial manufacture of clothespins, of a new type, having inwardly extending resilient tongues on the legs of the clothespins, formed by and between the central kerf and reverse kerfs at each side of the central kerf. This style of clothespin is more particularly shown and described in Patent No. 1,274,236 of July 30, 1918.

The primary object of our present invention is to provide a comparatively simple machine for manufacturing clothespins of this type, which can be operated at such a rate of output as will insure a uniform and satisfactory product, which can be sold at a reasonable price.

One difficulty met with in manufacturing clothespins of the type referred to, has been in symmetrically and reliably cutting the reverse kerfs which form the spring tongues in the legs of the pins, and produce a substantially uniform product and, therefore, a further object of our improvement is to provide for widening the central kerf at the crotch thereof, by means of a broach, so as to provide suitable shoulders, such as will enable the reverse kerfs to be readily started by the entering narrow ends of tapering longitudinally extending saw blades, provided for cutting the reverse kerfs.

A further object is to provide continuously moving pushers for moving a series of clothespin blanks, in a continuous line through the machine, so that the successive blanks are operated upon first to cut the central kerf, then to broach the crotch thereof and finally to cut the reverse kerfs on each side of the central kerf, the reverse kerfs being formed as the pushers carry the clothespin blanks over a pair of parallel saw blades,

extending practically the full length of the 55 machine, beyond the broach.

In a machine of this character, it is necessary that the clothespin blanks are fed to and through the machine, with the heads in the same relative position, and a further object 60 of our improvement is to provide delivery mechanism and rectifying means for delivering successive clothespin blanks in upright position singly and in front of the continuously moving pusher bars. 65

The mechanisms for carrying out these and other objects are more particularly shown in the accompanying drawing, representing one form of our improved clothespin machine. Fig. 1 represents a longitudinal 70 sectional view partly in side elevation, the partial section being taken along the line 1—1 of Fig. 3; Fig. 2 shows a clothespin blank and the successive steps to the finished clothespin; Fig. 3 is a top plan view of the 75 machine; Fig. 4 is an enlarged broken away vertical sectional view, substantially on the line 4—4 of Fig. 8; Fig. 5 is a horizontal 80 sectional view of the escapement mechanism on the line 5—5 of Fig. 4; Fig. 6 is an enlarged perspective view of the escapement drive mechanism, with parts broken away; Fig. 7 is a detail in perspective of the safety 85 connection in the blank delivery device; Fig. 8 is an enlarged broken away plan view of 85 the machine, more particularly showing the escapement and rectifying devices; Fig. 9 is a perspective view of the rectifying guides and delivery grooves; Fig. 10 is a plan view of the rectifying guides and grooves; Fig. 90 11 is a broken away detail of the ends of the delivery grooves, and the centering guides, associated with the circular saw; Fig. 11^a is a detail view of the centering guides removed from their support; Fig. 12 is a 95 broken away vertical sectional view of the left end of the machine, showing the clothespin blank delivery mechanism and devices associated with the circular saw; Fig. 13 is a partial sectional view of the clothespin 100 blank drum on the line 13—13 of Fig. 12; Fig. 14 shows, in perspective, a few of the peripheral plates and the door construction of the clothespin blank drum; Fig. 15 represents a partial vertical section, through 105 the circular saw, substantially on the line 15—15 of Fig. 1; Figs. 16, 17 and 18 represent vertical transverse sections of the

broach and saw blades for cutting the reverse kerfs, and their support, the sections being taken respectively, on the lines 16—16, 17—17 and 18—18 of Fig. 1; Fig. 19 shows 5 a broken away perspective of the reverse kerf saw blades and their support; Fig. 20 shows, in perspective, broken away details of various devices associated with the circular saw; Fig. 21 shows a perspective of the 10 first step of operation on the clothespin blank just passing over the circular saw; Fig. 22 is a perspective view showing the 15 second step or operation of broaching the crotch of the central kerf; Fig. 23 shows, in perspective, the third step in the operation, wherein the reverse kerfs are cut by the tapering saw blades and Fig. 24 shows a perspective of one of the pusher bars and associated parts.

20 Referring to the drawings, it will be seen that our improved machine preferably comprises an elongated bed mounted upon legs or standards 1, the bed preferably comprising parallel side bars or rails 2, which 25 may be connected together by suitable transverse ribs or shoulder bolts 3, as shown in Figs. 1 and 3 of the drawings. The side rails 2 of the bed provide supports for the various parts of the machine, including 30 bearings for transverse shafts 4 and 5, which are located at the ends of the bed rails 2. Each of the shafts 4 and 5 is provided with two sprocket wheels 6, secured to the respective shafts and carrying end- 35 less sprocket chains 7, the chains being located at each side of the machine, adjacent the side rails 2. A transverse shaft 8 is also mounted in bearings supported by the side rails 2, and carries a circular saw 9 for 40 cutting the central kerf of clothespin blanks as hereinafter described. The shaft 8 is preferably provided with a pulley 10, at one end (see Fig. 3), which is driven by a belt 11 from a motor 12, or any other 45 suitable source of power. The shaft 8 is also provided with a pulley 13 at its other end, which is connected by a belt 14, with a pulley 15 mounted on a shaft 16, as indicated in Fig. 3 of the drawings. The pulley 50 15 is adapted to drive the sprocket wheel shaft 4, through intermediate reducing gears 17 and 18, the arrangement being such that the sprocket chains are moved continuously longitudinally of the machine 55 (from left to right as seen in Figs. 1 and 3), at a uniform rate and at a speed considerably less than the speed of rotation of the circular saw 9.

60 The finished clothespins require a flaring or V-shaped opening at the lower ends of the legs, so as to facilitate entrance of the clothesline, and in our present machine, it is found desirable to make this bevel cut by means of cutters 19, mounted on each side 65 of the circular saw 9 in suitable openings

20 in the latter, as more particularly shown in Figs. 1 and 15 of the drawings.

After cutting the central kerf and the bevels at the lower ends thereof, by means of the circular saw 9 and cutters 19, it is 70 desirable, as previously stated, to widen the crotch of the central kerf to provide shoulders to facilitate the entry of and properly starting the saw blades in cutting the reverse kerfs. Accordingly, a broach 21 (see Figs. 1 and 22) is mounted on the end of a supporting plate or rail 22, which is cut away at 23, under the broach to provide clearance for the escape of cuttings from the broach. As shown in the drawings, the broach tapers from the width of the central kerfs, made by the circular saw, to the width required for the entry of the saw blades for cutting the reverse kerfs, see 80 view C of the Fig. 2.

Immediately succeeding the broach 21, the supporting plate 22 carries two long tapering saw blades 24, as indicated in Figs. 1 and 16 to 19, these saws being located on each side of the rail plate 22, which is preferably provided with a cap bar 25, held in place thereon by a tongue and groove, the respective saw blades 24 being secured to the cap bar 25, by means of screws 26, as more particularly shown in Fig. 19. It will be noted that the saws 24 flare out slightly and equally from the side walls of the centrally located rail plate 22, so when the reverse kerfs are cut they form upwardly extending wedge shaped or tapering tongues in the legs of the clothespin, as indicated in view D in Fig. 2. The supporting cap bar 25 with the combined thickness of the two saws 24 is of such a thickness or width as to enter the broached cut at the crotch of the central kerf, and the entering ends of the saws 24 are adapted to engage the offset shoulders of the broach cut to start the reverse kerfs. As indicated in the drawings, the cutting edges of the tapering saws 24 extend at an angle to the backs of the saws, secured to the cap bar 25, so that as the clothespin blanks are pushed longitudinally of the saws 24 and bar 25, the latter will ride in the broached crotch, while the tapering cutting edges of the gradually widening saws 24 will cut the reverse kerfs in the legs of the clothespin. The rail plate 22 is preferably substantially the thickness of the central kerf, made by the circular saw 9, and obviously in moving the blanks longitudinally of the saws 24, the latter are apt to bind as the reverse kerfs become deeper and, therefore, in order to relieve this pressure or binding, the rail plate 22 is preferably cut away on each side at 27 to provide parallel longitudinal shoulders or ribs 28, lying slightly above the cutting edges of the saws 24 and extending throughout the length of the saws, 100 105 110 115 120 125 130

parallel to their tapering cutting edges. This arrangement is more particularly indicated in Figs. 17 to 19.

As previously stated, the rail plate 22 is, 5 in the present instance, approximately the thickness of the central kerf, cut in the clothes pin blanks by the circular saw 9, and is mounted in the plane of the saw, so that blanks may be moved successively over 10 the circular saw 9, the broach 21 and the saw blades 24 in a straight line. For this purpose the rail plate 22 is supported centrally of the machine, between the sprocket chains 7 by suitable standards or posts 29, 15 which project upward from cross bars 30, located transversely of and supported by the side bars or rails 2 of the main frame of the machine.

For continuously feeding blanks through 20 the machine for the successive operations of cutting the central kerf, the broached crotch and the reverse kerfs, the continuously driven sprocket chains 7 are preferably provided with a plurality of pusher bars 31, the 25 ends of which are secured to the respective chains 7, the pusher bars being equally spaced throughout the length of the driving chains, and carried along thereby in parallel relation. In order to maintain the pusher 30 bars 31 in upright position and cause them to travel through the top of the machine in a straight line, parallel to the backs of the saw blades 24, or parallel to the cap bar 25 supporting said saws, the ends of the respective 35 pusher bars are preferably provided with elongated slide plates 32 (see Fig. 24), which are adapted to slide in grooves 33, cut longitudinally of strips or bars 34, mounted upon upright posts 35 extending upward from the 40 main frame side rails 2, substantially as indicated in Figs. 4 and 12. In that the sprocket chains 7 are endless and travel continuously, the pusher slide plates 32 pass out of the grooves 33 at the right hand end of 45 the machine, as viewed in Fig. 1, and, returning under the bed of the machine, are brought again into position to enter the grooves 33, the ends of the latter are preferably made V-shaped at 36 to facilitate the 50 proper entry of the pusher slides into the grooves 33.

The pusher bars 31, as more particularly shown in Figs. 4 and 24, are provided with a vertically disposed U-shaped pusher element 37, which is bifurcated at the open end thereof, to straddle the saws and broach. Preferably the legs or lower ends of the U-shaped pusher element 37 are provided with inwardly projecting lugs 38, which just 55 clear the saws and these lugs, as well as the upper yoke portion of the U-shaped pusher element, are provided with recesses at 39 and 40 respectively, for centering and holding the lower and upper ends of the blanks. 60 By this arrangement it will be seen that the

continuously moving pusher bars 31 are adapted to move the clothespin blanks from the position indicated in Fig. 20, over the circular saw 9, to the position shown in Fig. 21 and then to the position shown in Fig. 22, 70 carrying it over the broach 21; and finally over all the way along the saw blades 24, as shown in Figs. 1 and 23. Thus by successive operations on the blank, the finished clothespins are produced with the central and reverse kerfs, substantially as shown at D in Fig. 2.

It will be understood that preferably there is a continuous series of clothespin blanks, 80 passing through the machine to be operated on successively, as previously described, and the number of blanks so operated upon in a given time may be determined by the speed of the chain drive moving the pusher bars 31 and the spaced relation between successive pusher bars. In order to provide for a continuous series of blanks going through the machine and placed in front of successive pusher bars, before or by the time they arrive in front of the circular saw 9, as indicated in Fig. 20, it is necessary to provide means for reliably delivering such blanks singly and in proper synchronism to be engaged by the respective pusher bars 31. It is also necessary, in delivering and placing 90 the clothespin blanks in front of the pusher bars, that the heads shall be up. To properly insure the delivery and rectification of successive clothespin blanks, we have devised special feeding and delivering means, 100 the operation of which is synchronized with the motion of the pusher bars 31.

In order to supply clothespin blanks to the machine continuously as required, a vertically disposed chute 41 is preferably supported above the pusher bars, on standards 42, substantially as indicated in Figs. 4 and 12 of the drawings, the thickness of the chute being such that the blanks lie one above another in a single layer. This chute 105 41 is preferably kept filled with a predetermined number of blanks by means of a suitable feeding device or hopper. In the present instance, the chute 41 is preferably supplied with clothespin blanks arranged 110 horizontally, so as to drop into the chute in that position, by means of a rotating drum 43, supported centrally above the machine and over the chute 41, by a bracket 44, (see Fig. 3). The drum 43 is adapted to be rotated by a pulley 45, driven by a belt 46, extending over a pulley 47 on the end of the sprocket wheel shaft 5. The drum 43 preferably comprises two circular discs 48 and 49, between the peripheries of which are 115 mounted a plurality of off-set overlapping plates 50, which are suitably supported by the discs 48-49 to form the cylindrical peripheral portion of the drum, with a corresponding plurality of sinuous channels and 120 125 130

openings therein for the release of blanks, to be dropped into the chute 41. The arrangement of the plates 50 are more particularly shown in perspective in Fig. 14. The openings at 51 between the step-like overlapping plates 50 are closed by doors 52, for holding the blanks in single file in the sinuous channels between the plates 50 substantially as indicated in Fig. 12 of the drawings. At the inner ends of the peripheral plates 50, guide plates 53 are preferably mounted between the disc walls 48-49 for assisting in arranging the blanks in parallelism and directing them into the channels between the plates 50, where they lie in single file parallel to the axis of the drum. The peripheral doors 52 are preferably provided with operating arms or levers 54 located on the outside of the drum wall 48, and are here shown as extending beyond the circumferential edge thereof. The lever arms 54 of the respective doors 52 are provided with springs 55, connected therewith in a manner to hold the doors closed during rotation of the drum, but permitting release of blanks when desired, by the actuation of the lever arms 54.

For opening the doors 52, to release clothespin blanks in position to fall into the vertical chute 41, a trip member 56 is pivotally mounted in bearing brackets 57, located on the wall of the chute 41, substantially as indicated in Fig. 12. It will be noted that the trip 56 is arranged to normally stand in the path of the lever arms 54, so as to engage the latter successively as the drum is rotated, thereby releasing the blanks singly and in succession, in position to drop into the chute 41. Suitable resilient means is provided for holding the trip 56 in tripping position, this being accomplished in the present instance by the weighted arm 58. In actual operation of the machine, it is found that it is frequently not required to trip successive levers 54 to open the respective doors 52, for in that case, more blanks may be released than are required to fill the chute 41. Therefore, the trip 56 is provided with a downwardly extending trigger arm 59, which enters a slot 60 in the wall of the chute 41, in position to be engaged by the clothespin blanks, and when the chute 41 contains a predetermined number of blanks, the trigger will be forcibly held out of the passage of the chute, thereby holding the trip 56 out of the path of the door lever arms 54. With the trip 56 in this position, the drum will rotate without releasing blanks until additional blanks are required in the chute 41.

As previously explained, the blanks, for efficient and continuous operation of the machine, are required to be delivered from the chute 41 at regular intervals and one at a time. For this purpose, the bottom of the chute is preferably provided with a ro-

tary delivery member 61 controlled by an escapement. The delivery member 61 comprises a cylindrical trough adapted for holding a single blank, as indicated in Fig. 4, and rotatably mounted in bearings 62, the latter being utilized to properly position the chute 41 and for securing it to a cross bar 63, mounted on top of the standards 42, as shown in Figs. 4 and 12. The trough-like delivery member 61 is adapted to be rotated intermittently, being temporarily held against rotation, with the trough upward, to receive a blank and after being rotated 180° is again temporarily held, so as to allow time for the release and delivery of the blank. The intermittent rotation of the delivery member 61 is controlled by a suitable escapement mechanism, mounted in the bearing block 64, the latter also serving as a bearing for the shaft 65, which is connected with the delivery member 61 for rotating it.

The shaft 65, within a cavity in the block 64, is provided with a dog 66, adapted to cooperate with a pair of dogs 67, mounted on opposite sides of the shaft 65 on a slide bar 68, which is adapted to slide horizontally in slots in the block 64, as indicated in Figs. 4 to 6 of the drawings. The shaft 65 passes through and finds bearing in a tubular shaft 69, rotatably supported in a bearing block 70, and provided at its outer end with a sprocket wheel 71, which, by means of a chain 72 and sprocket wheel 73, is adapted to be driven from the shaft 5 of the sprocket wheels 6, carrying the endless chains 7, forming the motive power for the respective pusher bars 31, which are adapted to move the clothespin blanks through the machine for the various operations thereon.

It will thus be seen that in this manner the rotation of the sprocket wheel 71 and tubular shaft 69 is synchronized with the motion of the pusher bars 31 through the machine. The tubular shaft 69 and sprocket 71 are connected to the shaft 65 for intermittently rotating the latter and the delivery member 61, by means of a coiled spring 74. Rotation of the shaft 65 will be intermittently prevented by the engagement of the dog 66 with one or the other of the holding dogs 67, during which time the spring 74 will be wound up. In order to release the shaft 65, for its intermittent rotation of 180°, the slide bar 68, carrying the dogs 67, is adapted to be reciprocated by means of an eccentric 75 mounted on the tubular shaft 69 and provided with an eccentric strap 76 on the end of a pitman 77 pivotally secured at 78 in one end of the slide bar 68, to thereby move the latter transversely of the shaft 66 back and forth once during each revolution of the sprocket wheel 71. In this manner, the dogs 67 al-

ternately hold and release the shaft 65; its connecting delivery member 61 being thus given a half revolution intermittently, while the sprocket wheel 71 is rotated continuously.

It is found in practice that the clothespin blanks are not always of uniform diameter, and on this account or otherwise, the delivery member 61 might, at times, become jammed, and to prevent damage to the machine, the shaft 65 is preferably connected to the delivery member 61, by a yielding connection, which comprises a flat spring 79, secured to the end 80 of the delivery member 61, by means of a screw 81, the end of the spring being adapted to engage a flattened portion 82 of the shaft 65, which enters a suitable hole in the end 80 of the delivery member, substantially as shown in Figs. 4 and 7 of the drawings. By this arrangement, it will be seen that if the delivery member 61 becomes blocked or jammed and fails to respond to normal rotation, the spring 79 will be forced upward, permitting the shaft 65 to rotate without injury to the mechanism.

As more particularly shown in Fig. 4 of the drawings, the clothespin blanks are assembled in the chute 41, with their heads lying in either direction and it is necessary that they be delivered and positioned in front of the pusher bars 31 in vertical position with their heads up, therefore, specially designed grooved guides or tracks are provided for this purpose. The transverse supporting plate 63 is provided with a slot at 83 and immediately below this slot, two substantially vertical grooves in tracks 84 and 85 are secured and spaced apart, so as to be located near the ends of the slot 83, in position to engage the heads of clothespin blanks released by the delivery member 61. The grooves in the track members 84 and 85 are narrower than the body of the blank, thereby engaging the neck below the head while the opposite end of the blank, not being able to enter the other groove, will cause the blank to cant as the head end moves down its groove. Under the influence of gravity, the blanks will thus move downward between the tracks 84 and 85 at an angle, substantially as indicated by the blanks shown in dotted lines in Fig. 4. The tracks 84 and 85 diverge slightly at their lower ends and the latter are curved outward into a horizontal position, so that as a clothespin blank falls, with its head engaged by one of the guide grooves, it will be swung into vertical position, suspended by its head. One of the blanks is shown in full lines in Fig. 4, just swinging into vertical position.

The guide grooves in the curved lower ends 86 of the grooved tracks 84 and 85 merge with horizontal guide grooves 87 and

88, extending lengthwise of the machine, parallel to the path of the pusher bars 31. The guide grooves 87 and 88 converge V-like in a track plate 89, as shown more particularly in Figs. 8 to 11 of the drawings. 70 Bridge pieces 90 and 91 extend over the guide grooves 87 and 88 for supporting the outer rails of the respective grooves, which converge into a single groove at 92. The latter is preferably extended by means of 75 spring fingers 93. At the point where the grooves 87 and 88 merge with the single groove 92, it is desirable to have the respective grooves made continuous, so as to continuously engage the head and keep the 80 blank from dropping, and for this purpose, a switch member 94 is provided. This member 94, as will be seen in Figs. 10 and 11, is formed as a wedge-shaped finger, pivoted to the plate 89 at 95, and adapted 85 to be moved in one direction or the other by the blanks, as they are moved in singly along the respective grooves 87-88. The blanks, after entering the horizontal grooves 87-88, are adapted to be moved along the 90 grooves by means of bars 96, secured to the upper ends of the lugs 37 on the pusher bars 31, as will be seen in Figs. 10 and 11.

The rearward or converging end of the horizontal track plate 89 is supported by a 95 plate 97, to which it is secured by screws 98, engaging the bridges 91, as more particularly shown in Figs. 8 and 12. The plate 97 extends longitudinally of the machine, immediately above the circular saw 9, and is 100 supported by transverse bars 99 and 100, which lie above the plate 97 and are supported by posts extending upward from the bed side rails 2. The underside of the plate 97, from above the end of the single guide 105 groove 92 to a point beyond the circular saw 9, is recessed at 101 (see Figs. 12 and 20), and mounted in this recess is a grooved plate 102, which is provided with two upwardly projecting studs 103. The studs 103 110 pass through holes in the plate 97 and are pivotally connected with bell crank levers 104, rocking in fulcrum brackets 105, secured to the top of the plate 97. The upper ends of the bell crank levers 104 are connected together by a link 106 to thereby provide a parallel motion device for moving the grooved plate 102, up and down in parallel relation to the plate 97, by which it is supported. 115

The longitudinal groove in the movable plate 102 is parallel with and centrally located with reference to a vertical plane through the circular saw 9, and the heads of clothespin blanks, under the push of pusher bars 31, are adapted to enter the groove of the plate 102 as they leave the track groove 92 between the spring fingers 93, substantially as shown in Figs. 12 and 20. A spring 125 107, connected to the end of the link 106 and 130

to a fixed pin 108, is adapted to resiliently hold the groove plate 102, in contact or engagement with the head of the blank.

Lying parallel to the plate 97, below it, and provided with a slit through which the circular saw projects, there is mounted a table or platform 109, adapted to engage the lower ends of clothespin blanks, as they move out of the single guide groove 92 and throughout their engagement with and passage over the circular saw 9 for cutting the central kerf. The resilient groove plate 102, pressing down on the heads of blank, is therefore, adapted to hold successive blanks in contact with the saw table 109 and provide for any slight variation in the lengths of the blanks.

Although the blanks carried along by the respective pusher bars 31 are centered in the sockets 39 and 40 in the U-shaped lugs 37, it is desirable to insure correct centering of the lower ends of the blanks on the table 109 before the blanks are actually brought into engagement with the circular saw 9. For this purpose, a pair of guide plates 110 is mounted on the forward end of the table 109, as more particularly shown in Fig. 11 of the drawings. These guide plates are arranged to slide laterally and longitudinally by angular tongue and groove or pin and slot connections at 111, the arrangement being such that as the guide plates 110 are forced angularly outward and rearward, the space therebetween will widen, while the guides hold the lower end of the blank centrally with respect to the circular saw 9. In order that the two guide plates 110 shall move simultaneously and to the same extent, they are connected together by interlocking brackets 112, secured to the respective plates and in sliding engagement on the underside of the saw table 109, (see Figs. 4 and 11^a). Springs 112^a connected to the plates 110 and to the plate 109 tend to contract the plates 110 together.

The operation of the machine will be understood from the description thus far given, and it will be seen that as the clothespin blanks are received and straightened in the drum 43, they will be released therefrom, one at a time, and drop into the chute 41, from which they will be delivered singly by the intermittent rotation of the delivery member 61, controlled by the escapement 66—67, which, as previously explained, is operated intermittently in synchronism with the chain driven pusher bars 31. The blanks, as released by the delivery member 61, will drop downward and according to the direction of the head, the latter will engage one or the other of the guide grooves in the upright tracks 84—85. The blank will then fall by gravity and be swung into vertical position in front of one of the pusher bars 31, where it will be engaged by

the transverse pusher plate 96, and carried along one or the other of the horizontal track grooves 87—88 into the central groove 92. At this point the blank A becomes seated in the centering sockets 39 and 40, and further movement of the pusher bar carries the blank on to the table 109, where its lower end is centered by the guides 110, as the head enters the groove in the resilient guide plate 102. Further movement of the pusher bar 31 carries the blank over the circular saw 9, to form the central kerf 113 and the bevel 114 at the lower ends thereof, as shown at B on Fig. 2. The thin end of the broach 21 then enters the crotch of the kerf 113 and further movement of the pusher bar 31 forces the blank over the broach and forms the shouldered wide crotch, as shown at 115 in the view C in Fig. 2. It will be understood that the pusher bars 31 move continuously, and immediately after the blank as shown at C in Fig. 2, passes off of the broach 21, the narrow ends of the saws 24 will enter the widened opening 115 and engage the shoulders thereof on each side of the central kerf 113. Continued movement now of the pusher bar 31 carries the clothespin blank longitudinally of the saws 24, the blank being held down to the crotch by the action of the cutting edges of the saws, which thereby produce the reverse kerfs 116, as shown at D in Fig. 2. The completed clothespin, as shown at D in Fig. 2, is thus provided with inwardly projecting resilient tongues 117 on each side of the central kerf 113. Clothespins after completion pass off the ends of the saws 24 and drop by gravity and may be collected in any suitable manner.

While we have shown and described one form of our improved clothespin machine, it will be understood that we do not wish to be limited to the specific construction shown, for obviously various modifications may be made in the details thereof and in the arrangement and adaptation of various features of construction, without departing from the spirit and scope of the invention.

We claim:

1. A clothespin machine comprising a centrally arranged saw for cutting a central kerf in clothespin blanks, a pair of stationary longitudinally extending saws for cutting reverse kerfs from the crotch of the center kerf down each leg of the clothespin, one of said pair of saws being arranged on each side of the plane of the said central saw, and a power-driven member for moving the clothespin blanks over said saws to produce the respective kerfs.

2. A clothespin machine, comprising a circular saw for cutting a central kerf in clothespin blanks, a pair of longitudinally extending saws uniformly spaced apart throughout their length, one on each side

of the plane of said circular saw, for cutting reverse kerfs from the crotch of the central kerf down each leg of the pin, and power driven pusher elements for moving 5 the clothespin blanks over said saws.

3. A clothespin machine, comprising a circular saw for cutting the central kerf in clothespin blanks, cutters carried by said saw for beveling and flaring outward the 10 lower end walls of said central kerf, a broach for increasing the width of said kerf at the crotch thereof, a pair of tapering saw blades adapted to enter said broached cut at the crotch, for cutting a reverse kerf 15 down each leg of the pin, and power actuated pushers for moving clothespin blanks over said circular saw, said broach and said pair of saw blades in succession.

4. A clothespin machine, comprising a 20 plurality of uniformly spaced pusher elements, adapted to be moved continuously for moving clothespin blanks uniformly through the machine, a chute for holding a supply of said blanks, means operated in synchronism 25 with said pusher elements for releasing blanks singly from said chute, and means for placing said released blanks in upright position in front of said pusher elements in succession as the latter pass under said chute.

5. The clothespin machine as claimed in 30 claim 4, in which said means for placing released blanks in front of said pusher elements comprises means engaging the heads of said blanks for rectifying them, as they fall by gravity, so that they are placed before said pusher elements with the heads up.

6. The clothespin machine, as claimed in 40 claim 4, in which said means for releasing blanks from said chute comprises a rotatable delivery element for releasing said blanks one at a time.

7. In a clothespin machine, the combination 45 with means for positively and uniformly moving a succession of single clothespin blanks in a straight line through the machine, of a circular saw against and over which the successive blanks are moved for cutting central kerfs therein, a platform extending on each side of said saw, parallel to 50 the direction of motion of the blanks, said platform being adapted to engage the lower ends of said blanks and support them as they are carried over the saw, and means for holding the blanks in engagement with said platform.

8. The clothespin machine as claimed in 55 claim 7, in which the receiving end of said platform is provided with centering guides for centering the blank with respect to the saw.

9. The clothespin machine as claimed in 60 claim 7, in which said means for holding the blanks in engagement with said platform comprises a grooved plate mounted over said saw and parallel with said plat-

form, the groove in said plate being adapted to engage the heads of the blanks, and resilient means is provided for urging said plate toward said platform to thereby hold the blanks in contact with the latter as they 70 pass over the saw.

10. In a clothespin machine, the combination of a plurality of pusher bars, adapted to be moved longitudinally of the machine in equally spaced succession, means for feeding clothespin blanks singly and in upright position in front of successive pusher bars to be carried along thereby, each pusher bar being provided with a socket for engaging and centering the blanks, a saw for cutting 75 central kerfs in the blanks as they are moved along by said pusher bars, and a pair of saws for cutting reverse kerfs on each side of the central kerf, the last named kerfs extending downward into the legs of the 80 pin to thereby form upwardly projecting resilient tongues on each side of the central kerf.

11. In a clothespin machine, the combination with a circular saw for cutting central 90 kerfs in clothespin blanks, a table for supporting the blanks as they are moved over said saw, a pair of opposed centering guide plates movably mounted at the entering end of said table, for centering the clothespin 95 blanks with respect to the saw, means connecting said plates to adapt both of them to expand away from each other in unison equal distances from the central plane of the saw when an expanding force is exerted 100 upon either of them, and means tending to contract the plates together.

12. In a clothespin machine, the combination with a circular saw, for cutting central 105 kerfs in clothespin blanks, a table for supporting the blanks as they are moved over the saw, a plate mounted above said saw and provided with a groove central of and parallel to the plane of said saw, said plate being adapted for movement toward and from said table in parallel relation thereto, a spring for urging said plate toward the table, to thereby hold said blanks in contact with the latter, and means for moving the blanks along said table and over said saw.

13. In a clothespin machine, the combination with saws for cutting central and reverse kerfs in clothespin blanks, of means for continuously moving a series of blanks over said saws, a chute for holding blanks 110 for delivery one at a time, in horizontal position, a pair of vertically grooved guides for receiving blanks from said chute, said vertical grooves being adapted to engage the heads of the blanks, so that they may 115 swing into upright position by gravity, horizontal guides provided with grooves merging with the respective vertical grooves, said horizontal grooves converging into a single groove, the arrangement being such that 120 125 130

blanks released from said chute, with heads in either direction, will be rectified and pass into one or the other of said horizontal grooves suspended by the head, means associated with said continuously moving means for engaging the blanks so positioned and moving them along the respective horizontal grooves into the single groove, and means for holding said blanks in centered position 10 after they leave said single groove.

14. In a clothespin machine, the combination with a chute for receiving and holding clothespin blanks, of a rotating blank delivery member at the bottom of said chute, 15 means for rotating said member intermittently, an escapement for holding said member against rotation, power means for actuating said escapement to release said member for intermittent rotation, means for moving blanks, delivered from said chute, through the machine, and connections between said last named means and said escapement power means for synchronizing the movements thereof.

15. The clothespin machine as claimed in claim 14, in which means is provided between said escapement and the rotating delivery member of the chute for permitting rotation of said intermittently rotating 30 means independently of said delivery member, in case the latter should become clogged by said blanks.

16. In a clothespin machine, the combination of a saw for cutting central kerfs in successive clothespin blanks fed through the machine, a pair of tapering saw-blades extending longitudinally of the machine for cutting reverse kerfs on each side of the central kerf, a rail plate between and supporting said saw-blades, said rail plate being provided with shoulders following the taper cutting edges of the saw-like blades, the thickness at said shoulders being substantially the width of said central kerf, where 45 by the pressure is relieved on the tongues formed as said reverse kerfs are cut.

17. A machine for performing a shaping operation upon clothespin blanks comprising shaping means, means to feed blanks to said shaping means upright and in spaced relation, a chute adapted to hold blanks in a horizontal position, a rotatable member adapted to release the blanks one at a time from the chute, means operated in synchronization with said blank-feeding means adapted to rotate said rotatable member intermittently to release a blank, and means to place the released blank in an upright position and deliver it to the said feeding means.

18. A clothespin machine comprising a pair of longitudinally extending stationary saws uniformly spaced apart throughout their length and adapted for cutting kerfs from the crotch of the central kerf down 60 each leg of the pin to produce flexible

tongues, power driven means for moving the pin along said saws, and means for guiding the pin in its movement along the saws and maintaining its legs in proper relation to the saws.

70

19. A clothespin machine comprising a broach supported in a fixed position and adapted for increasing the width of the central kerf of the pin at its crotch, a pair of longitudinally extending saws supported in fixed positions spaced apart throughout their length and adapted to enter said broached cut at the crotch for cutting a reverse kerf down each leg of the pin, and power driven means for moving the pin along said broach 80 and along said pair of saws for the broaching and cutting operations.

75

20. In a machine for performing a shaping operation upon headed clothespin blanks, the combination of shaping means, means for holding blanks and delivering them one at a time in horizontal position, a pair of vertically grooved guides for receiving blanks from said holding means, said vertical grooves being adapted to engage the heads of the blanks so that they may swing into upright position by gravity, horizontal guides provided with grooves merging with the respective vertical grooves, said horizontal grooves converging into a single 90 groove, the arrangement being such that blanks released from the said holding means with heads in either direction will be rectified and pass into one or the other of said horizontal grooves suspended by the head, and means for engaging the blanks so positioned and moving them along the respective horizontal grooves into the single groove and to the said shaping means.

95

21. In a clothespin machine the combination of means for positively moving a succession of single clothespins in a straight line and in spaced relation, and a pair of saws mounted in fixed positions and extending longitudinally in the path of movement of the pins, said saws being spaced apart throughout their length and adapted to cut reverse kerfs from the crotch of the central kerf of each pin down each leg thereof during the said movement of the pins.

100

22. A machine for cutting a reverse kerf from the crotch down one of the legs of a clothespin comprising a stationary saw adapted to enter the crotch of the clothespin, and means for moving the pin along the saw in a straddling relation thereto to form said kerf.

110

23. A machine for cutting a reverse kerf from the crotch down one of the legs of a clothespin comprising a stationary tapered saw adapted to enter the crotch of the clothespin, said saw increasing in depth from its entering end, and means for moving the pin along the saw in straddling relation thereto to form said kerf.

115

120

125

130

24. A machine for cutting a reverse kerf from the crotch down one of the legs of a clothespin, comprising means for moving the pin in a straight line, a stationary saw extending longitudinally in the path of movement of the pin and adapted to enter the crotch thereof, and means for moving the pin along the saw in straddling relation thereto to form said kerf.
- 10 25. A machine for cutting a reverse kerf from the crotch down one of the legs of a clothespin comprising a stationary broach adapted for enlarging the opening at the crotch of the pin, a stationary saw adapted to enter said broached out crotch of the pin, and means for moving the pin along the broach and along the saw in straddling relation thereto in succession to form said kerf.
- 20 26. A machine for cutting reverse kerfs down the legs of a clothespin comprising a pair of stationary longitudinally extending saws spaced apart throughout their length and diverging transversely, and means for moving a clothespin longitudinally along the saws in straddling relation thereto to form said kerfs.
- 30 27. A machine for cutting reverse kerfs down the legs of a clothespin comprising a pair of stationary saws adapted to enter the crotch of the pin, and a pusher element movable along said saws and adapted to carry the pin with it along the saws in straddling relation to them to form said kerfs, the said pusher element being formed to straddle the saws and engage the legs of the pin.
- 40 28. A machine for cutting reverse kerfs down the legs of a clothespin, comprising means for moving the pin along a straight line, a pair of stationary saws extending longitudinally in the path of movement of the pin, said saws diverging transversely and said pin-moving means being adapted to move the pin longitudinally along the saws in straddling relation thereto to form said kerfs.
- 50 29. A machine for cutting reverse kerfs down the legs of a clothespin comprising a pair of longitudinally extending stationary saws spaced apart throughout their length, and means for moving a clothespin along said saws in straddling relation thereto and in a straight line to form said kerfs, the longitudinal cutting edges of the saws extending along lines inclined with relation to the path of the pin, whereby the kerfs will be cut through the legs from the crotch of the pin toward the free ends of the legs as the pin is moved along the saws.
- 60 30. A machine for cutting reverse kerfs down the legs of a clothespin to form tongues extending upwardly at the inner sides of the legs, said machine comprising a pair of saw blades tapering in depth, a stationary longitudinally extending straight rail plate located between said saws and supporting them with their saw edges spaced outwardly from the opposite side faces of the plate, and means for moving a clothespin along said saws in straddling relation thereto to form the kerfs, the said rail plate being adapted to contact the inner sides of the legs of the pin below the cutting edges of the saw blades and guide the pin as it is moved along the saws, and the plate being narrowed above the cutting edges of the saws to provide clearance for the said tongues as they are formed.
- 70 31. A machine for cutting reverse kerfs down the legs of a clothespin comprising a pair of saw blades tapering in width, a stationary longitudinally straight rail plate between said saws and supporting them in transversely diverging positions with their cutting edges spaced from the opposite faces of the plate, and means for moving a clothespin along said saws in straddling relation thereto to form the said kerfs, the said rail plate being formed to contact the inner sides of the legs of the pin below the cutting edges of the saw blades to guide the pin as it is moved along the saws.
- 80 32. A machine for cutting reverse kerfs down the legs of a clothespin comprising a pair of longitudinally extending stationary saws spaced apart throughout their length, and means for moving a clothespin along said saws in straddling relation thereto and in a straight line to form said kerfs, the longitudinal cutting edges of the saws extending along lines inclined with relation to the path of the pin and the saws diverging transversely, whereby the kerfs will be cut from the crotch of the pin downwardly in diverging directions as the pin is moved along the saws.
- 90 33. A machine for cutting reverse kerfs down the legs of a clothespin comprising a stationary broach, a pair of stationary saw blades located in alignment with said broach and tapering in width, means for moving a clothespin along the broach and the saws in straddling relation to them, and means to guide the pin in its movement and maintain the legs thereof in proper relation to the saw blades, the said broach being adapted to enlarge the opening at the crotch of the pin, and the tapered saws being spaced apart and adapted to have their narrow ends enter the broached out crotch in position to start the cutting of said kerfs, whereby as the pin is moved over the length of the saws the kerfs will be formed.
- 100 34. In a clothespin machine the combination of means for positively moving a succession of clothespins in a straight line and in spaced relation, broaching means mounted in a fixed position in the path of movement of the pins and adapted as each pin is moved over it to increase the width of the central
- 110
- 120
- 130

kerf thereof at its crotch, and a pair of saws mounted in fixed positions and extending longitudinally in the path of movement of the pins, said saws being spaced apart throughout their length and adapted as each pin is moved over them to enter the said broached opening and cut reverse kerfs down each leg of the pin.

35. A machine for cutting reverse kerfs down the legs of a clothespin, comprising means for moving a clothespin in a straight line, and a pair of saws mounted in fixed positions extending longitudinally in the path of movement of the pin and spaced outwardly transversely at opposite sides of a central line, said saws being adapted to enter the crotch of the pin and cut reverse kerfs down each leg thereof during said movement of the pin.

20 36. A machine for cutting reverse kerfs down the legs of a clothespin comprising a pair of saw blades tapering in width, a longitudinally straight rail plate between said saws and supporting them in transversely diverging positions with their cutting edges spaced from the opposite faces of the plate, and means for moving a clothespin along said saws in straddling relation thereto to form the said kerfs, the said rail plate being 25 formed to contact the inner sides of the legs of the pin below the cutting edges of the saw blades to guide the pin as it is moved along the saws.

37. A machine for cutting reverse kerfs down the legs of a clothespin comprising a broach, a pair of saw blades located in alignment with said broach and tapering in width, means for relatively moving a clothespin along the broach and along the saws in straddling relation to them, and means to maintain the legs of the pin in proper relation to the saw blades, the said broach being adapted to enlarge the opening at the crotch of the pin, and the tapered saw blades being

spaced apart and adapted to have their narrow ends enter the broached out crotch in positions to start the cutting of the kerfs whereby as the pin is relatively moved lengthwise of the blades the kerfs will be cut.

38. A machine for cutting a reverse kerf down one of the legs of a clothespin, comprising a longitudinally extending saw blade adapted at one end to enter the crotch of the pin, means for supporting the pin in straddling relation to the saw blade, means for supporting the saw blade with its cutting edge directed from the crotch of the pin toward the free end of said leg obliquely with relation to the inner side of the leg, and power driven means to cause a relative movement between the pin and the saw blade in a direction longitudinally of the saw blade to cut said kerf.

39. A machine for cutting reverse kerfs down the legs of a clothespin comprising a broach, a pair of tapered saw blades located in alignment with the broach and increasing in width from the end adjacent the broach, a longitudinally straight rail plate between 70 said saws and supporting them in transversely diverging positions with their cutting edges spaced from the opposite faces of the plate, and means for relatively moving the clothespin along the broach and along 75 the saws in straddling relation thereto to form said kerfs, the broach being rigidly carried by the rail plate and said plate being formed to contact the inner sides of the legs of the pin below the cutting edges 80 of the saw blades to guide the pin as it is relatively moved along the saws.

In testimony whereof we hereunto affix our signatures this 9th day of February, 1925.

HENRY J. KAHRS.
